UNITED STATES PATENT OFFICE.

HERMAN BERGLUND, OF MAHTOWA, MINNESOTA, ASSIGNOR OF ONE-HALF TO
LAWRENCE COMPAGNE, OF DULUTH, MINNESOTA.

MEANS FOR SECURING KNIFE-BLADES TO A KNIFE-BAR.

1,218,511.

Specification of Letters Patent.

Patented Mar. 6, 1917.

Application filed April 21, 1916. Serial No. 92,689.

To all whom it may concern:

Be it known that I, HERMAN BERGLUND, a citizen of the United States, residing at Mahtowa, in the county of Carlton and 5 State of Minnesota, have invented new and useful Improvements in Means for Securing Knife-Blades to a Knife-Bar, of which the following is a specification.

This invention relates to means for securing 10 knife blades to a knife bar, and it consists in the novel features hereinafter described and claimed.

An object of the present invention is to 15 provide an efficient means for holding the knife blades upon a knife bar in the cutting apparatus of a mowing or like machine, and the present invention is designed to be used to advantage as a substitute for the rivets which are now commonly used for accomplishing the same purpose.

Incident to the use of rivets several disadvantages exist, among them being that when it is desired to remove one or more knife blades from the bar it is necessary to 20 cut the rivets and punch them out of the knife blades and bar. This operation frequently expands the bar and consequently the bar has to be dressed or reshaped when new knife blades are placed thereon. By 25 the use of the present invention there is no possibility of expanding the bar or distorting its shape by removing the knife blades therefrom, and furthermore, the blades may be easily and quickly removed for substitution or sharpening.

With the above objects in view the present invention consists in providing upon the knife bar fixed studs adapted to pass transversely through the knife blades. Some of 40 the said studs are longer than others, and the longer studs are threaded at their upper ends and project above a strip which is positioned at the upper sides of the knife blades. Nuts are screw threaded upon the 45 threads of the extended studs. The knife bar is provided at its rear edge with an upstanding flange with which is hingedly connected a bar adapted to swing over the said strip, the said bar being provided with recesses 50 which snugly receive the said nuts and prevent the same from turning after they have been set in position above the strip. The said bar, when closed down upon the strip, extends rearwardly beyond the

flange and is adapted to lie over the forward 55 edge of the cutter bar, and thus it is held in position when the knife bar is placed in its supports of the cutting apparatus.

In the accompanying drawing:

Figure 1 is a top plan view of a portion 60 of the blade securing means.

Fig. 2 is a transverse sectional view of the same cut on line 2—2 of Fig. 1.

Fig. 3 is a fragmentary plan view of the 65 same with parts in section.

Fig. 4 is a similar front view with parts in section.

Fig. 5 is a transverse sectional view cut on the line 5—5 of Fig. 3.

As illustrated in the accompanying drawing, the knife bar 1 is provided at its rear edge with an upstanding flange 2 disposed at right angle to the body portion of the bar. Studs 3 pass transversely through the forward portion of the bar 1 and are fixed 70 with relation to the same. Some of the studs 3 are longer than others, and the longer studs are threaded at their upper ends as at 4. The knife blades 5 are of the usual configuration and are provided in the vicinity of 75 their rear edges with openings which receive the studs 3.

A metallic strip 6 lies upon the upper surfaces of the rear portions of the blades 4 and is provided with openings which receive 85 the upper portions of the studs 3. The upper ends of those studs which are not threaded are flush with the upper surface of the strip 6, while the upper ends of the threaded studs project above the upper surface of 90 the strip 6. Nuts 7 are screwed upon the threaded ends 4 of the said projecting studs and the lower faces of the nuts bear in close contact against the upper surface of the strip 6.

A bar 8 is hingedly connected with the upper portion of the flange 2 in any suitable manner and the said bar is adapted to swing over the strip 6 and lie in close contact with the same when the parts are assembled. The bar 8 is provided at its under side and in the vicinity of its forward edge with recesses 9 which snugly receive the nuts 7 and hold the said nuts against turning movement upon the studs on which they are 100 mounted. The flange 2 of the knife bar 1 is located in advance of the forward edge of the finger bar 10 of the cutting apparatus

and when the forward portion of the bar 8 is swung down in close contact with the upper surface of the strip 6, the rear portion of the said bar 8 lies over the forward edge portion of the cutter bar 10 and in close contact with the same as shown in Fig. 2 of the drawing.

In operation the bar 10 remains stationary while the bar 1 is reciprocated back and forth in front of the same in the usual manner.

When it is desired to remove one or more of the blades 5 for substitution, sharpening or other purposes, the knife bar 1 is detached from the machine and then the bar 8 may be swung freely from over the strip 6. By using a wrench the nuts 7 may be unscrewed from the threaded ends of the studs 4 and thus the knife blade 5 and the strip 6 are liberated. After lifting the strip 6 from over the upper ends of the studs 3, any particular knife 5 may be removed by lifting it off the said stud. Then another knife may be substituted in its stead or in case the removed knife is repaired or sharpened it may be replaced. During this operation it will be seen that no strain whatever is applied to the knife bar 1, consequently the said bar is not distorted and when the parts are assembled upon the machine they fit accurately and may be operated without undue friction.

From the above description taken in conjunction with the accompanying drawing it will be seen that simple and efficient means is provided for holding the knife blades in position upon a knife bar and that the device may be easily and quickly manipulated for the purpose of removing one or more of the knife bars and replacing others or the

same without injuring the parts of the device.

Having described the invention what is claimed is:—

1. In a cutting apparatus a knife bar provided at its rear edge with an upstanding flange, studs mounted upon the knife bar, knife blades having openings receiving the studs, a strip lying upon the knife blades and having openings which receive the studs, some of the studs having threaded portions extending above the strip, nuts screwed upon said extended portion and a bar hingedly connected with the flange at the upper rear edge thereof and having recesses which receive the said nuts. 45 50 55

2. In a cutting apparatus a knife bar having at its rear edge an upstanding flange, studs mounted upon the knife bar, knife blades having openings which receive the studs, a strip lying transversely across the knife blades and having openings which receive the studs, some of the said studs having threaded portions which extend above the upper surface of the strip, nuts mounted on said extended portion and a bar hingedly connected with the flange at the upper rear edge thereof and having recesses adapted to receive the nuts the last mentioned bar also having a portion disposed behind the rear 65 70 75 surface of the flange and adapted to lie above the finger bar of the cutting apparatus.

In testimony whereof I affix my signature in presence of two witnesses.

HERMAN BERGLUND.
